COMBINED RANDOM ACCESS STORAGE AND RETRIEVAL UNIT

William E. Pascale, 1784 Frobisher Way, San Jose, Calif.
95124, and Jack W. Stringer, 17830 Daves Ave., and
John D. Jagger, 16585 Topping Way, both of Los Gatos,
Calif. 95030

Filed Oct. 13, 1965, Ser. No. 87,467

Term of patent 14 years

(Cl. D26—5)

FIG. 1

FIG. 2

FIG. 3

FIG. 4

FIG. 5

FIG. 1 is a front perspective view of a combined random access storage and retrieval unit showing my new design;

FIG. 2 is a top plan view thereof;

FIG. 3 is a front elevation view thereof;

FIG. 4 is a left side view thereof;

FIG. 5 is a right side view thereof.

The rear side of FIG. 3, the side not shown is substantially plain and unornamented.

We claim:

The ornamental design for a combined random access storage and retrieval unit, as shown and described.
